UNITED STATES PATENT OFFICE

CLIFFORD C. HUNT, OF JACKSON, MICHIGAN, ASSIGNOR TO REYNOLDS SPRING COMPANY,
OF JACKSON, MICHIGAN, A CORPORATION OF DELAWARE

DESIGN FOR A SPOON OR SIMILAR ARTICLE

Application filed October 12, 1932. Serial No. 45,321. Term of patent 7 years.

To all whom it may concern:

Be it known that I, CLIFFORD C. HUNT, a citizen of the United States, residing at Jackson, in the county of Jackson, and State of Michigan, have invented a new, original, and ornamental Design for a Spoon or Similar Article, of which the following is a specification, reference being had to the accompanying drawing, forming part thereof.

Fig. 1 is a side elevation of a spoon showing my new design.

Fig. 2 is a front elevation of the design shown in Fig. 1.

The dominant feature of my design consists in a head and front quarters of a mammal shown in relief and constituting the outer end of a handle for spoons or similar articles.

I claim:

The ornamental design for a spoon or a similar article substantially as shown and described.

CLIFFORD C. HUNT.
